UNITED STATES PATENT OFFICE.

THOMAS J. HAYES, OF CLEVELAND, OHIO, ASSIGNOR TO WILLIAM A. HORGAN, OF BOSTON, MASSACHUSETTS.

PUMP.

1,114,689.

Specification of Letters Patent.

Patented Oct. 20, 1914.

Application filed January 5, 1912. Serial No. 669,598.

To all whom it may concern:

Be it known that I, THOMAS J. HAYES, a citizen of the United States, residing at Cleveland, in the county of Cuyahoga and 5 State of Ohio, have invented certain new and useful Improvements in Pumps, of which the following is a full, clear, and exact specification.

This invention relates to a pump for 10 pumping a fluid, particularly air, and is adapted for operation by connection to the cylinder of an explosion engine.

It is of particular value for pumping air into the tires of automobiles and other vehicles operated by hydro-carbon engines, but it is obvious that it may be used for other purposes.

The invention presents a device of exceeding simplicity of construction easily and 20 cheaply constructed, and one of great efficiency.

The nature of the invention will more 25 fully appear from the accompanying description and drawings, and will be particularly pointed out in the appended claims.

The drawings illustrate a preferred form 30 of the invention adapted for use in connection with an automobile.

In the drawings: Figure 1 is a view of 35 the entire device chiefly in central cross-section; Fig. 2 is a detailed view showing the means for preventing relative rotation of the sleeve and casing. Fig. 3 is a detail showing the device adapted for connection with a pet cock in the engine cylinder.

In the form of the device shown 1 is the casing of the pump preferably cylindrical, as shown, and exteriorly screw-threaded at each end, as indicated at 2, to provide for 40 the attachment thereto of the heads 3 and 4 respectively which form part of the casing. The head 3 is provided with a passageway through which the fluid compressed by the piston of the pump is discharged and means 45 are provided in this passageway for permitting discharge only therethrough. In the drawings the discharge passageway is shown as beginning at 5 and it extends out through the nozzle 6. In the passageway is located 50 a suitable check valve 7, the details of which are not involved in this invention as any suitable and well known form may be employed. The function of the check valve, as usual, is to permit the fluid to discharge 55 therethrough, but prevent its return into the

pump. A tube 8 is connected to the nozzle and leads to the device, such for example as an automobile tire, into which the fluid is to be pumped. The head 4 at the opposite end of the pump is provided with means for connection to the cylinder or explosion chamber of an explosion or hydrocarbon engine. Such means are shown as the pipe 9 threaded at one end into the head 4 and provided at its projecting end with a threaded portion 60 10 which may be inserted in the threaded socket provided in such engines for the sparking plug. The pump may also be connected to a pet cock such as usually provided in the engine cylinder. In such case, as 65 shown in Fig. 3, a reducing cap 30 is screwed into the head and this connection may readily be made to the threaded end of the pet cock.

Within the casing a sleeve 11 is located 75 and this sleeve fits closely the interior of the casing, but is capable of a limited longitudinal movement within the casing. The sleeve 11 is, therefore, shown as somewhat shorter than the length of the casing. Relative rotary movement between the sleeve and the casing is prevented by a pin 12 secured 80 in the casing 1 and extending into a longitudinal slot 13 in the sleeve 11. The sleeve and the casing are each provided with one 85 or more fluid receiving ports. The ports in the casing are indicated at 14 and those in the sleeve at 15. When the sleeve is at the engine end of its longitudinal movement, that is in the position shown in Fig. 1, these 90 ports are in alignment so that fluid, such as atmospheric air, may pass in through the ports into the interior of the pump. Upon the movement of the sleeve toward the discharge end of the pump these ports pass out 95 of alignment and the sleeve 11 closes the ports 14 against the admission of fluid. The piston is mounted to move longitudinally 100 within the sleeve and is of sufficient length and weight so that it will have a steady easy movement therein. In the form shown the piston comprises a heavy metal head 16 snugly fitting the interior of the sleeve, a stem 17, and a head made up of metal disks 18 clamped together by a nut 19, and clamping in place an interposed packing disk 20 105 of suitable material.

The action of the pump will be apparent from the foregoing description of a preferred form thereof. If, for example, it is 110

desired to pump up a deflated tire of an automobile, one of the sparking plugs is unscrewed from its socket and the threaded end 10 of the pipe 9 is secured into its place. 5 The tube 8 is connected with the valve of the tire. The parts of the pump will either be in the position shown in Fig. 1 or they will immediately assume that position upon suction taking place in the engine. Upon the compression stroke in the engine cylinder the piston and sleeve held together by the friction therebetween will move longitudinally toward the discharge end of the pump, closing the ports 14. The piston will then continue its movement compressing the air in front and forcing it through the check-valve 7. Upon the return stroke of the engine the pump, piston and the sleeve will move toward the engine end of the pump until the ports 14 and 15 are in alinement and the sleeve is in the position shown in Fig. 1, then the piston will continue its movement drawing air in through the alined ports until it reaches the end of its stroke. The pump 25 may be connected, as provided in Fig. 3, to a pet cock in the engine cylinder and then the explosion stroke of the engine made use of without cutting out the cylinder and enabling the pump to be applied to a one cylinder engine. 30

It is obvious that various changes may be made in the construction, shape and proportion of the parts without departing from the principle of this invention, as defined by the 35 claims.

Having thus fully described my invention what I claim as new and desire to secure by Letters Patent is:—

1. A pump adapted for operation by connection to the cylinder of an explosion engine comprising a casing, presenting a discharge passageway from one end, means for permitting only discharge through said passageway, means for connecting the opposite end of the casing to the engine cylinder, a sleeve fitting the interior of said casing and having a limited longitudinal movement therein, means for preventing relative rotary movement of said sleeve and casing, 40 ports in said sleeve and casing near the upper ends thereof which aline when the sleeve is at the engine end of the casing and which pass out of alinement upon the movement of the sleeve toward the discharge end, and a piston snugly fitting the interior of said sleeve, the friction between the piston and the sleeve securing the movement of the sleeve upon the movement of the piston. 45

2. In a device of the character described a casing, a sleeve fitting the interior of said casing and having a limited longitudinal movement therein, means for preventing relative rotary movement of said sleeve and casing, ports in said sleeve and casing near the upper ends thereof which aline when the 50 sleeve is at the engine end of the casing and which pass out of alinement upon movement of the sleeve toward the discharge end, and a piston snugly fitting the interior of said sleeve, the friction between the piston and the sleeve securing the movement of the sleeve upon the movement of the piston. 55

sleeve is at the engine end of the casing and which pass out of alinement upon the movement of the sleeve toward the discharge end, and a piston snugly fitting the interior of said sleeve, the friction between the piston 70 and the sleeve securing the movement of the sleeve upon the movement of the piston.

3. A pump adapted for operation by connection to the cylinder of an explosion engine comprising a casing, presenting a discharge passageway from one end, means for permitting only discharge through said passageway, means for connecting the opposite end of the casing to the engine cylinder, a sleeve fitting the interior of said casing and 75 having a limited longitudinal movement, ports in said sleeve and casing near the upper ends thereof which aline when the sleeve is at the engine end of the casing and which pass out of alinement upon the movement of the sleeve toward the discharge end, means for preventing relative rotary movement of said sleeve and casing, and a piston snugly fitting the interior of said sleeve, the friction between the piston and the sleeve 80 securing the movement of the sleeve upon the movement of the piston.

4. In a device of the character described a casing, a sleeve fitting the interior of said casing and having a limited longitudinal 95 movement therein, means for preventing relative rotary movement of said sleeve and casing, ports in said sleeve and casing near the upper ends thereof which aline when the sleeve is at the engine end of the 100 casing and which pass out of alinement upon the movement of the sleeve toward the discharge end, and a piston snugly fitting the interior of said sleeve, the friction between the piston and the sleeve securing the movement of the sleeve upon the movement of the piston.

5. A pump adapted for operation by connection to the cylinder of an explosion engine comprising a casing, a head detachably 110

mounted at one end thereof and provided with a discharge passage way, means for permitting only discharge through said passage way, a head detachably connected to the opposite end of the casing, adapted for 115 connection to the engine cylinder, a sleeve fitting the interior of said casing and having a limited movement therein, a longitudinal slot in the lower end of said sleeve, a pin secured to the casing and extending into said longitudinal slot whereby relative 120 rotary movement between the sleeve and the casing is prevented, ports in said sleeve and casing, near the upper ends thereof which aline when the sleeve is at the engine end of the casing and which pass out of alinement upon movement of the sleeve toward the discharge end, and a piston snugly fitting the interior of said sleeve, the friction between the piston and the sleeve securing the movement of the sleeve upon the movement of the piston. 125

movement of the sleeve upon the movement of the piston.

6. A pump adapted for operation by connection to an explosion engine comprising a casing, a head detachably mounted at one end thereof and provided with a discharge passage way, means for permitting only discharge through said passage way, a head detachably connected to the opposite end of the casing, a reducing cap mounted in said last mentioned head to permit connection to a pet cock of the cylinder of an explosion engine, a sleeve fitting the interior of said casing and having a limited movement therein, a longitudinal slot in the lower end of said sleeve, a pin secured to the casing and extending into said longitudinal slot whereby relative rotary movement between

the sleeve and the casing is prevented, ports in said sleeve and casing near the upper ends thereof which align when the sleeve is at the engine end of the casing and which pass out of alignment upon movement of the sleeve toward the discharge end, and a piston snugly fitting the interior of said sleeve, the friction between the piston and the sleeve securing the movement of the sleeve upon the movement of the piston.

In testimony whereof I have signed my name to this specification in the presence of so two subscribing witnesses.

THOMAS J. HAYES.
